UNITED STATES PATENT OFFICE.

HANS J. SWANSON, OF CHICAGO, ILLINOIS.

LEVEL AND PLUMB.

Application filed February 10, 1926. Serial No. 37,421.

This invention relates to certain novel improvements in levels and has for its principal object the provision of an improved construction of this character which will be highly 5 efficient in use and economical in manufacture.

Among the salient objects of the invention is the production of an instrument of this character wherein there is provided a simple 10 combination and arrangement of parts for illuminating the tubes of the instrument to facilitate observation of the tubes when the instrument is used in positions and places where a shadow is cast upon the level hindering 15 correct observation of the tubes or in places where there is not sufficient light to enable one to have proper sight of the tubes.

Other objects will appear hereinafter.

The invention consists in the combination 20 and arrangement of parts to be hereinafter described and claimed.

The invention will be best understood by reference to the accompanying drawings wherein the preferred form of construction 25 of my invention is shown and in which:

Fig. 1 is a perspective view of the invention illustrating the preferred form of construction.

Fig. 2 is a longitudinal vertical sectional 30 view of the same.

Fig. 3 is a fragmentary sectional view taken substantially on line 3—3 of Fig. 2.

Fig. 4 is a sectional view taken substantially on line 4—4 of Fig. 2.

Fig. 5 is a fragmentary sectional view taken substantially on line 5—5 of Fig. 2.

Fig. 6 is a sectional view taken substantially on line 6—6 of Fig. 2.

The invention in its preferred form of construction includes an oblong body 10 formed of the proper material and provided in its top surface 11 with a recess 12 and in an end portion a transversely extending hole 13 confined within which are the usual level tubes 12' and 45 13' respectively.

The level tube 12' is held in its confined position by a plate 14 secured to the body as at 50 15 and provided with a sight opening 16 permitting observation of this tube. The tube 13' is held in its confined position by a plug 17 formed of the proper material.

The body includes a side plate 18 formed of proper material and extending the full length of the body and of a width equal to the width 55 thereof. This plate serves as a cover for a compartment 19 formed in the body 10 as best

illustrated in Fig. 2. The body further is provided with a transversely extending opening 20 extending substantially at right angles with the hole 13 serving as a sight opening to 60 facilitate observation of the tube 13'.

The tubes 12' and 13' are illuminated by means of lamps 21 positioned in reflectors 22 which project into the compartment 19 and secured in position in the body by brackets 23 65 which engage the lamp receiving sockets 24 of the reflectors 22 as best illustrated in Figs. 3 and 6.

As best illustrated in Figs. 3 and 6 the brackets are arranged in pairs whereby they 70 can be separated when found necessary to remove the reflectors 22. As illustrated in Fig. 2 the body portions 22' of the reflectors are seated in recesses 25 formed in the body 10.

The end portion 10' of the body includes a 75 compartment 26 and in this compartment is confined an electric battery 27 which is connected in circuit with the lamps in a manner to be hereinafter described. The open end 27' of this compartment is closed by an end 80 plate 28 which is pivotally connected to the body 10 through the medium of a suitable connecting element 29. This end plate is slotted as at 30 for the reception of a securing element 31 carried by the body 10. This arrangement is such that when it is desired to remove the battery 27, the screw 31 is partially removed to permit the end plate to be pivoted about the element 29 to expose the battery through the open end 27' of the compartment 26. The opposite end of the body is 85 likewise provided with an end plate 32 which serves to protect this end of the body when the level is placed in a vertical position upon this end.

The battery is connected in circuit with approved push button switches 33 through the medium of conductor wires 33' connected to a conductor strip 34 having an angled end portion 35 in contact with the pole 36 90 of the battery as best illustrated in Fig. 2. The push button switches include casings 37 having the usual flanges 38 perforated to accommodate securing screws 39. The push button switches further include the usual 95 spring controlled push buttons 40 which extend through openings 41 formed in the cover plate 18 as illustrated in Fig. 5. These push button switches are connected in circuit with the lamps through the medium of conductor wires 42 and 43 connected to contact strips 44 having yieldable end portions 45 in con-

tact with the contact points 46 of the lamps as best illustrated in Fig. 6. The lamps are connected to the other pole 47 of the battery through the medium of conductor wires 48 having end portions connected to the brackets 23 engaging the socket receiving portions of the reflectors, and having opposite end portions connected to a conductor strip 49 extending through a recess 49' formed in the body 10 and provided with a resilient end portion 50 in contact with the pole 47 of the electric battery. By the use of separate push button switches the lamps can be independently connected in circuit with the electric battery 27 and independently illuminated.

The instrument is used in the usual manner known by those skilled in the art and in use, should the instrument be placed in a dark corner or in a position where a shadow is cast upon the lever, proper observation of the tubes can be had by pushing the push button of the switch controlling the lamp contiguous of the exposed portion of the tube under observation.

It is apparent that I not only provide a simple combination and arrangement of parts for illuminating the level tubes but that I also assemble the combination of elements in a manner whereby the elements can be expeditiously associated and removed from association with the body when required or found necessary.

While I have shown and described the preferred form of my invention, it is to be understood that various changes and alterations may be carried out in manufacture without

departing from the spirit of the invention or the scope of the appended claim.

The invention having been set forth, what I claim as new and useful is:

In a level structure, a body having a hollow interior and having openings adapted to receive level tubes, level tubes in said openings, said openings being in communication with said hollow interior, means for illuminating said level tubes including electric lamps, a web adapted to extend across one end of said hollow interior whereby to provide two compartments, a battery having terminals at opposite ends mounted in one of said compartments, a clip having one end portion secured in said hollow interior and having a portion extended through the other of said compartments and including a portion at the free end thereof adapted to extend downwardly into engagement with the terminal at the outwardly disposed end of said battery, another clip mounted in said interior and having a portion adapted to engage the terminal at the other end of said battery, means for connecting said clips and said lamps whereby to establish electrical connection between said lamps and said battery, said last named means having switches provided therein adapted to control operation of said lamps, and a movable plate at one end of said body portion adapted to close the outer ends of said two compartments whereby access may be obtained to the compartment having said battery mounted therein.

In testimony whereof I affix my signature.

HANS J. SWANSON.
